(57) **CLAIM**

The ornamental design for a surface for an article of manufacture, as shown and described.

DESCRIPTION

FIG. 1 is a front elevational view of a surface for an article of manufacture wherein, for purposes of illustration, the article of manufacture is a headboard;

FIG. 2 is a right side profile of a surface for an article of manufacture wherein, for purposes of illustration, the article of manufacture is a headboard, the left side profile being a mirror image thereof; and,

FIG. 3 is a top view of a surface for an article of manufacture wherein, for purposes of illustration, the article of manufacture is a headboard.

The broken lines are for environmental purposes only and form no part of the claimed design.
